UNITED STATES PATENT OFFICE

GERHARD A. KLEIN, OF LOS ANGELES, CALIFORNIA

DEVICE FOR DISPLAYING INTERCHANGEABLE ADVERTISEMENTS

Application filed May 14, 1929. Serial No. 362,999.

This invention relates to improvements in advertising and memento devices and has for its object to provide a simple, efficient and inexpensive device for displaying advertisements, announcements and the like in an effective manner.

One object of my invention is to provide a form of display device wherein the product or item of merchandise or any other item 10 permanently printed in a conspicuous place on the device may have associated movably therewith the name of the advertiser or brand of goods to the end that the movable part of the display device may serve not only to point out the fact that there is a shortage on hand of any particular item listed or classified on the display device, but the additional fact that the particular advertiser makes the product sought to be purchased 20 so that at the time the householder or other person is in a buying mood the suggestion to buy from the particular advertiser whose name is associated with the article needed will be made strong enough as can be thru 25 advertising publicity.

Another object of this invention is to display not only the name of the advertiser, but also a slogan associated with the article of merchandise in question and for this reason 30 one or more of the advertising indicia bearing elements are made movable from hidden to open display position whenever it is desired to point out the fact that an item is to be replenished in stock and it is desirable to 35 display the maker of the goods needed.

With the above and other objects in view my invention consists in the arrangement, combination and details of construction disclosed in the drawings and specification, and then more particularly pointed out in the 40 appended claims.

In the drawings, wherein similar reference characters designate similar parts throughout the respective views,

Figure 1 is a vertical side elevation of my invention,

Figure 2 is a top plan view thereof,

Figure 3 shows a name or sign plate with 45 its hinge,

Figure 4 is a fragmental side elevation showing some name plates,

Figure 5 is a side elevation of a single name plate,

Figure 6 is a view similar to Figure 5 with 55 the advertisement changed,

Figure 7 is a fragmental detail view of a guide for slidably receiving a ticket,

Figure 7a shows a group of two views, showing opposite sides of a single name 55 plate,

Figure 8 is a side view of a modified name or sign plate,

Figure 9 is a view similar to Figure 8 but showing the advertisement changed,

Figure 10 is a side elevation of a ticket or 65 slidable panel,

Figure 11 is another side elevation of an elongated slidable panel,

Figure 12 is a side view of a still further 70 modified form of a sign plate,

Figure 13 is a view similar to Figure 12 but showing the sign changed,

Figure 14 is a side elevation of a name 75 plate,

Figure 15 is a side view of another form of sign plate,

Figure 16 is a view similar to Figure 15 but showing the panels in extended position,

Figure 17 shows a group of three figures, 80 showing successively the sign plate proper, a section thru one end and guide, and a section thru another portion and guide.

In the drawings, which are merely illustrative of my invention 10 designates a panel board or display board or backing having a legend as "Grocery reminders" printed at the upper end thereof. Therebelow follows two vertical groups of columns of advertising signs, arranged in a consecutive classified series, of separate sets of advertising items, of which the item printed at the right of each set of horizontally alining columns designates the name of the food article and the item remaining in the set to the left designates the name of the maker or advertiser of the given item.

Thus at the right vertical column at 17 appear the names of consecutive items of food or merchandise and to the left thereof 95 100

pears the name of the advertiser as at 15. It should be noted that one side of each of a series of sign panels preferably made of metal is printed the name of the maker in black 5 against a white background, or colorless background as at 20 on the side 13 of this plate; while the opposite side 13a is painted with a conspicuous distinguishing color say red; on the uncolored side the name of the 10 article appears as at 18, while on the colored side the name of the brand of goods or of the advertiser clearly appears in display. It is predetermined that all items permanently printed on the right column directly 15 on the panel board 10 will be covered by a sign plate to cover them and to conceal them; and as the side of the plate exposed to view then contains the name of the item or article of food or merchandise, the same legend thus 20 appears. Now on the left side of the same panel board 10 appears the permanently inscribed name of the maker or advertiser of this item or article, so that an ad can be read at all times first containing name of 25 advertiser and then product put out by him. Each sign plate has a hinge collar 11 embracing a guide post 16 secured at its upper and lower ends 14 operatively to the panel board 10 a spring 15 being used if desired to 30 press all the collars together to afford spring resistance to the swinging movement of the individual name plates. With the name of article items on the right all covered up the significance of this arrangement is this; no 35 items are needed for replenishing stocks. Whenever it is to be essential to remind the householder or the like that there is a shortage of any material or item listed on the panel board, all it is necessary to do is to 40 swing the sign plate to position to overlie and conceal the name of the maker of the article in question as it appears printed on the panel board and thereupon the colored side or face of the sign plate is now exposed 45 to view with the result that the name of the maker is now exposed to display position in red color; and this denotes as by a red signal that the item mentioned and now uncovered to the left of the name or sign plate is 50 needed and should be repurchased, but the red color displayed brings to mind the name of the advertiser conspicuously.

Another form of my invention consists in providing each sign plate with a guide section, so that the one half 23 of the sign plate 55 has the name of the advertiser printed on it as at 22 on colored background 24, while the other half is of a double-wall construction 23, 19 to slidably receive and house the ticket 24 or slip 24a, the name of an article of food or merchandise being printed upon the display face 20 of this guide. Ordinarily when the slip 24a is projected out of the guide 23, 19 it covers the colored background and its advertiser-legends 22, and replaces the same with

the same name printed at 25 upon the slip, and now the full advertisement appears printed, but the signal is not used to denote a shortage of the item printed on the guide. Now by pushing the slip 24a into the guide 70 to uncover the colored background 24, then the full significance of the ad is had again, but this time the colored background signals the fact that there is a shortage of the item printed at 20 and brings to light the fact that 75 the advertiser puts out for sale this particular item; hence the advertising indicia is enhanced in value.

Another form of the invention just described consists of the main sign plate formed 80 with the double-wall guide 26 intermediate its ends receiving a ticket or slip 34 of a length to not only extend thru this guide but also to extend in either guide at the end of the sign plate, the last two guides being 85 formed by pressing out of the sign plate upper and lower guide flanges 32, 33, and 32a, 33a respectively so as to expose the legends between these flanges alternately. A handle 36 is provided at one end of the ticket or slip 90 34. At 27 is permanently printed the name of an article of merchandise on the guide 26; at 29 is printed the name of the advertiser proper, if desired; this legend 29 appears in a colored background 28; again a slogan 31 95 is printed at the other end of the guide in a colored background 30. At the end of the ticket opposite to the place where the handle 36 is found is located a stop lug 37 which serves as a stop limiting the ticket or slip 100 in its slidable movement.

The ticket 34 carries two advertising imprints; at 35 is printed some advertising legends. When the ticket is partially concealed in the guide 26, the colored part 30 of the ticket reveals the slogan 31 next to the name of the article advertised upon the display face of the guide 26; while the legend appearing at 29 on the sign plate identifies the name of the advertiser both with the article sold and with the slogan printed. When the ticket is drawn out of the guide it covers the legend 29, and now the advertisement legend 35 is exposed from the ticket, and the now uncovered advertising legend 38 of the 110 sign plate is displayed conspicuously to view.

A still further modification of the invention now described is concerned with the arrangement of parts exactly as shown in point of physical construction in Figures 8 and 9 115 but differs in the advertising impressiveness created. The difference is simply this; one half of the ticket is white and the other half is colored and this is true likewise of the end legend-bearing parts of the sign plate.

In Figures 14, 15 and 16 the construction of sign plate or display plate is such that the central portion is of two-walled formation providing the guide portion 26; but instead of single ticket 34 being movably and slidably 120

lodged in this guide portion two tickets of a length slightly greater than the guide portion 26 are provided, designated 41, 42 and each may bear the imprint of an advertisement or memento indicia; the terminal portions flanking the guide portion 26 may be calibrated as at 38, 39 respectively for the purpose of specifying any item of merchandise to be conveniently inventoried; by the simple act of sliding the two tickets out of the guides, and extending them so as to overlie any of the calibrated items the desired information may be conveyed in timely manner to those interested.

From the foregoing it will be seen that I have provided an efficient device for changing the advertisement of any maker of merchandise, where color helps in making the display of advertising effective. I do not mean to limit myself to the exact details of construction shown but cover all changes falling within the scope of the appended claims.

What I claim and seek protection on is as follows:

1. In a device as described the combination of a plate having one half of its length formed into a casing open medially of the plate, the other half thereof being colored, there being an inscription upon the outer face of the casing, and another inscription upon the colored part thereof, and a panel having an uncolored outer face bearing an inscription, said panel being enclosed and concealed in said casing but being slidable thereout so as to cover the colored plate part and reveal in advance of and in line with the casing its own inscription.

2. A sign display device consisting of an elongated plate formed at one end with a guide, the outer face of the plate, to one side of the guide bearing an advertising inscription, the outer face of the guide also bearing an advertising inscription, and a slidable strip movable into a concealed relation into the guide so as to be hidden from obstructing view relatively to the first inscription, the outer face of the movable strip also bearing a colored advertising inscription, said strip designed to move out of the guide to cover the inscription on the plate to one side of the guide and reveal its own inscription.

In witness whereof he has hereunder set his hand this 29 day of April, 1929.

GERHARD A. KLEIN.
